UNITED STATES PATENT OFFICE.

FRED R. C. PITZLER, OF LESTER PRAIRIE, MINNESOTA.

WASHING-MACHINE.

SPECIFICATION forming part of Letters Patent No. 593,118, dated November 2, 1897.

Application filed June 8, 1897. Serial No. 639,241. (No model.)

To all whom it may concern:

Be it known that I, FRED R. C. PITZLER, of Lester Prairie, in the county of McLeod and State of Minnesota, have invented a new and Improved Washing-Machine, of which the following is a full, clear, and exact description.

My invention relates to improvements in that class of washing-machines in which the casing forming the clothes-chamber may be placed with its axis vertical when the articles to be washed are inserted or removed and may then be turned so as to have its axis horizontal while it is in use, and has for its object the production of a new and improved device of this character, whose novel arrangement and construction of parts will now be described, and particularly pointed out in the appended claims.

Reference is to be had to the accompanying drawings, forming a part of this specification, in which similar characters of reference indicate corresponding parts in all the figures.

Figure 1 is a perspective view of the machine, showing in dotted lines the filling position of the cylinder. Fig. 2 is a cross-section of the cylinder, showing a portion of the end partition which separates the clothes-receiving chamber from the chamber containing the gear-wheels as broken away. Fig. 3 is a longitudinal section through the cylinder. Fig. 4 is a detail section through the shaft or central portion of the cylinder. Fig. 5 is a detail cross-section of the cylinder-shaft, showing the beaters attached thereto; and Figs. 6 and 7 are respectively a side and an end elevation of the cylinder carrying the beaters so arranged that it may be revolved in either direction.

A framework A, composed of bars joined together in such manner as to form a substantial support for the machine, is provided and has pivoted therein a cross-bar A', which at its center has a vertical bar A⁴, joined at its outer end to a cross-bar A², the latter being parallel with the pivoted bar A'.

The bar A' is hinged upon the pivots a, whereby the frame composed of the bars A', A², and A⁴ may be swung down to the horizontal position, as shown by dotted lines in Fig. 1. The upper ends of the vertical posts of the main frame are notched to receive the ends

of the bar A² when the same is swung to the vertical position. This limits the swing of said bar in that direction.

To the ends of the bar A² are pivoted posts A³, which maintain a vertical position when the bar A² is swung down to the position shown in dotted lines. These posts support the bar A² and the cylinder B.

The shaft D is fixed to the bar A⁴ and does not turn. The cylinder B is mounted to rotate upon the sleeve E, which in turn is free to rotate upon the shaft. This cylinder is divided into two sections, the smaller one B³ being next to the bar A⁴. This section B³ contains the gear-wheels by which the mechanism of the washing-machine is operated.

The partition B² between these two chambers should be made water-tight to prevent water passing from the larger or clothes-receiving chamber to the smaller chamber B³. The larger chamber is provided upon its inner periphery with a series of longitudinal ribs b, and the heads B² B⁴ of the cylinder are also provided with radial ribs b². The head at the end opposite the chamber B³ is provided with a filling-opening b', through which the clothes are inserted and removed, and this opening is provided with a suitable door by which it may be closed and made substantially water-tight. The head B⁴ is also provided with a knob or handle b³, by means of which the cylinder may be turned.

Upon the inner periphery of the cylinder, within the chamber B³, is placed an internal-toothed spur-gear C. Mounted upon the shaft D within the said chamber is an arm D', which at its outer end carries a spur-gear C', meshing with the gear C, and fixed to the end of the sleeve E is a spur-gear C², which meshes with the gear C'.

It is evident from the proportion of the parts that if the cylinder B be turned upon its axis the sleeve E will be rotated more rapidly than the cylinder and in an opposite direction.

The sleeve E is provided with two longitudinal flanges F, located opposite each other and to which are attached beaters consisting of bars G, which are fixed upon chains g, which in turn are attached to the flanges F by means of apertures f therein. The outer ends of the

chains *g* are free. The bars may be strung upon any flexible connector as well as upon a chain.

As the sleeve *E* rotates the beaters *G* will be revolved and thrown outward by centrifugal force, striking against the clothes which are held against the inner periphery of the cylinder *B*. As a consequence the clothes will receive a rapid pounding and rubbing, which will quickly cleanse them of all dirt.

When the machine is being filled with clothes or water, the cylinder *B* is swung down to a horizontal position. After being filled it is swung to the upper position, (shown by full lines in Fig. 1,) in which the axis of the cylinder is horizontal. The cylinder is then rotated upon this axis, which operation rapidly cleanses the clothes.

The construction shown in Figs. 2, 3, 4, and 5 is one in which the device is intended to be rotated in one direction only, while Figs. 6 and 7 show a modification of the sleeve *E* and the attachment of the beaters thereto, which adapt it to be rotated in either direction. This construction is exactly the same as that heretofore described, except that the longitudinal flanges *F* have been removed from the sleeve *E* and the beaters *G* attached directly to the said sleeve.

It is of course to be understood that in Figs. 4, 5, 6, and 7 the beaters are not shown in full length, but have been curtailed. They are shown in full length in Fig. 2.

Having thus fully described my invention, I claim as new and desire to secure by Letters Patent—

1. In a washing-machine, a framework having uprights or posts, a normally vertical section formed of two cross-bars and a central bar connecting said cross-bars, said section

having one of said bars pivotally mounted between said posts, whereby it may be swung down to a horizontal position, legs pivotally attached to said section and by which it may be supported in such horizontal position, said legs folding up against said posts or uprights when the said section is vertically placed, a shaft attached to said central bar and run out at right angles thereto, and a clothes-holding washing-chamber mounted to rotate upon said shaft, as and for the purpose set forth.

2. A washing-machine, comprising a cylinder divided into two water-tight sections, one of which forms the washing-chamber and is provided with ribs upon its inner periphery and ribs upon its heads and radiating from the center thereof, a shaft upon which said cylinder is mounted to revolve, said shaft being capable of being swung to both a horizontal and a vertical position, and gearing in the other section, as and for the purpose set forth.

3. A washing-machine, comprising a cylinder divided between its heads into two water-tight sections, one of which forms the washing-chamber, a shaft upon which said cylinder is mounted to revolve, a sleeve surrounding said shaft and provided with flexible beaters, a handle attached to the outer head of said cylinder, and gearing in the other section of said cylinder and by which the sleeve is rotated in an opposite direction from said cylinder when the latter is turned by means of said handle, as and for the purpose set forth.
